NAIL EXTRACTOR

Hans Schultheiss, Weissenstadt, Germany

Application November 16, 1936, Serial No. 111,140
In Germany November 12, 1935

1 Claim. (Cl. 254—27)

The present invention relates to a device whereby nails may be extracted from boxes, boards and the like.

The tools known heretofore for fulfilling this purpose, but which only did so inadequately, were of different construction, and an absolutely noiseless extraction of the nail, which can only take place when the nail retains its straight shape, was not possible. The known nail extractors have also the drawback that they become absolutely useless as soon as the gripper becomes worn or breaks under excessive strain; moreover, these tools are lacking in further devices which are often used before or after drawing the nails, namely, a tool for scratching off useless labels or one for severing iron hoops, wire or the like.

These drawbacks are eliminated by the present invention by a new type of tool. The supporting foot arranged pivotally on the lever is provided, transverse to its direction of motion with a wide sharp foot, alongside which several sharp points can be included, so that after placing on a board, it can turn about these points as an axis of rotation but always in the same plane. The rotary movement of the lever about its axis is limited at both sides by stops in the supporting foot. A tension spring pulls the bottom lever arm against one of the stops, that is against the back one, in order to ensure a certain position of the tool with respect to the particular nail before manipulation. Thus the supporting foot cannot unintentionally move, nor can it be shifted when the tool is applied. According to a further feature of the invention, in order that a gripper can be exchanged for a new one, or a gripper for rather large nails exchanged for one for smaller nails, the lever can be provided with a gripper at each of its two ends, or, at the end of the lever, the actual gripping portion which contains the gripping jaw can be made interchangeable, or several such members, adapted to different nail sizes, are arranged on a drum or the like.

The need for being able to adapt the gripper to different nail sizes is also considered, according to the invention by providing only one gripper instead of several but cutting the slit intended to receive the nail, so far into the lever that the side portions formed by the slit tend to separate from each other. They can then be set to a certain width of slit by a pin provided with an adjusting screw.

According to a still further feature of the invention, besides a sharp edge for scratching off

labels, the supporting foot is also provided with a cutter which can be used for severing wire, iron hoops and the like. This cutter is preferably so arranged at one of the side lugs of the foot that it has its cutting edge directed somewhat inwards, that is, toward the longitudinal axis of the lever. It is provided with a pin which serves the cutter as a support during its lever-like actuation.

Of course, it is within the scope of the invention to provide the lever with a gripper at one end only whilst the other end is furnished with a handle, for example of wood.

In order to use the device, it is so applied that the lifting jaw lies shortly in front of the nail. Now if the long lever arm is forced downwards in its longitudinal direction and at the same time somewhat backwards, the lifting jaw slides noiselessly under the nail, which is then pulled out perfectly straight by further depressing the lever.

Practical embodiments of the object of the invention are illustrated in the drawing.

Fig. 1 is a nail extractor in side elevation.

Fig. 2 a view from below, and

Fig. 3 a front elevation.

Fig. 4 illustrates an element which can be reversibly inserted in the end of the lever and may be provided with slots of different sizes,

Fig. 5 a drum with three claws which can be fixed rotatably in the end of the lever,

Fig. 6 a vertically slotted lever with adjusting device, and

Fig. 7 shearing device with supporting pin, shown in side elevation, in position for use.

The nail extractor consists of the lever and the foot rotatably associated with it.

The lever 1 may be straight or somewhat angular in shape at its two ends, and provided at each end with a hole 2, adjacent which it is formed as a gripper 3 having a jaw 4. Running downwards in the latter is a slot 5 with suitably sharp edges.

The foot is rotatably mounted about the spindle 6 which is passed through one of the holes 2. This foot consists of a piece of thick sheet metal, so shaped that the bottom face 7 runs out into a sharp edge 8 and has a few triangular points 9 pressed out of it in downward direction. By moving the foot member about its fulcrum to the right as viewed in Figure 1 approximately 90 degrees, the edge 8 may be used to scratch a label or the like from the surface 15. The two side lugs 10 bent upwards, receive the spindle or pin 6. The bottom face 7 is also provided with

a gap 11 through which the lever 1 is passed and whose edges 12, 13 limit the course of the lever at each end.

The lever is continually pulled against the edge 5 13 of the gap 11 by a tension spring 14 stretched between it and the foot.

In Fig. 4, the end of the lever 1 has a conical opening 17 as the bearing socket for a suitably shaped knee-piece 18, which is inserted by one 10 end whilst having its other end acting for use as a gripper; both ends are shaped as gripping claws, that is, they are furnished with a jaw 4 and a slot for receiving the nail. The knee-piece can be inserted the other way round and 15 when in use, is fixed in the bearing socket 17 by a screw 19.

Fig. 5 shows the end of the lever 1 provided with a drum 21 rotatable about the spindle 20 and having three jaws 4 as grippers. It can be 20 fixed in the particular position for use by a locking pin 23 urged by the pressure of the spring 22.

Fig. 6 shows a lever which is slit down its 25 length, its two halves 24 being forced apart either by the springing of the material or by a special spring, whilst a wing nut 25 in conjunction with a pin 26 which replaces the spindle 6 makes it possible to adjust the width of the slit as required.

Figs. 1, 2 and 7 illustrate the cutter 27 for 30 severing wire, iron hoops, etc. It is secured to one of the side lugs 10 or is formed in one piece with same. Its cutting edge 28 is turned inwards somewhat, that is, towards the axis of the lever 1 whilst at the semi-circular rear portion, a pin 35 29 is provided as a support.

To use the device, the nail extractor is placed 40 on the board 15 (Fig. 1) in such a way that the jaw 4 lies close in front of the nail 16 and the spikes 9 press into the board. Now the lever arm 1 is pressed downwards and at the same time backwards, so that the sharp edges of the slot 5 slide under the nail head at both sides. Upon further depressing the lever, the tensile 45 force of the spring 14 is gradually added so that both forces together bring about a vertical ex-

traction of the nail until the lever arm strikes against the edge 12. By then, however, the nail is entirely, or at least for the greater portion, extracted.

When it is desired to cut a band or hoop, the 5 tool (Fig. 7) is placed with the supporting pin 29 on the edge of the case 30 in such a way that the edge 28 of the cutting knife 27 fits under the hoop 31. Now if the lever 1 is depressed, the 10 hoop 31 is severed, the lever together with the 15 hand operating it being guided downwards along the side of the case owing to the oblique setting of the cutter.

Having thus described my said invention, what I claim as new therein and desire to secure by 15 Letters Patent is:

A nail extractor comprising a foot member having a substantially triangular portion terminating in a relatively wide surface engaging base providing a fulcrum and when in operative position extending at an upward inclination from said fulcrum through and beyond the vertical plane of a nail to be extracted from said surface, said portion having an opening adjacent the apex opposite said base and in a plane midway between the side extremities of the base, downwardly and rearwardly inclined projections adjacent the side extremities of said base, a lever pivotally connected intermediate its ends to the foot member adjacent the vertical plane of the nail and extending substantially vertically through said opening, a nail engaging element at the lower end of the lever, said lever being pivotally movable forwardly and rearwardly relative to the foot member and the front and rear edges of said opening providing stop means below the horizontal plane of the pivot for limiting such pivotal movement of the lever in opposite directions, and a tension spring connecting the lever above the pivot with the foot member forwardly 40 of the pivot for automatically forcing the lever against the stop means at the rear edge of said opening preliminary to the rearward pull on the lever to extract a nail.

HANS SCHULTHEISS.
